UNITED STATES PATENT OFFICE.

EDMUND M. IVENS, OF NEW ORLEANS, LOUISIANA, ASSIGNOR TO EMILY L. IVENS, OF SAME PLACE.

LOG-PULLING APPARATUS.

SPECIFICATION forming part of Letters Patent No. 498,655, dated May 30, 1893.

Application filed June 16, 1892. Serial No. 437,006. (No model.)

To all whom it may concern:

Be it known that I, EDMUND M. IVENS, residing at New Orleans, in Orleans parish and State of Louisiana, have invented a certain 5 new and useful Log-Pulling Apparatus, of which the following is a specification.

My invention relates to an apparatus especially adapted for pulling heavy logs out of swamp lands into lagoons or bayous.

10 In collecting heavy logs from swamp lands, particularly so in the Louisiana swamps, great difficulty is experienced in handling heavy cypress logs, and pulling them through the swamp and brush to a collecting lagoon or 15 bayou; so much so, that much of the timber is allowed to remain, as its removal by the ordinary means is unprofitable.

My invention has for its object to provide 20 an apparatus which will effectively serve to collect such logs, at a profit, which can be constructed at a moderate cost and is easily operated.

To these ends my invention consists in the 25 peculiar and novel arrangement and combination of parts all of which will hereinafter be fully described in the specification and particularly pointed out in the claims, reference being had to the accompanying drawings in which—

30 Figure 1 is a top plan view of my improved log pulling apparatus. Fig. 1^a is a diagrammatic plan view of my improved apparatus as arranged for use. Fig. 2 is a longitudinal section on an enlarged scale of one of the 35 drums and the clutch devices. Fig. 3 is a detail transverse section taken on the line 3—3, Fig. 2. Fig. 4 is a front view, Fig. 5 a top view and Fig. 6 a side view of the rope laying devices. Fig. 7 is a detail view of one 40 of the feed screws hereinafter specifically referred to, and Fig. 8 is a sectional elevation of the steam cylinder and clutch lever operating pistons hereinafter referred to. Fig. 8^a is a top, and Fig. 8^b a sectional view of the 45 "swamp" sheave hereinafter referred to. Fig. 9 is a detail view of the main drive pinion, and Fig. 10 is a detail view of a modification hereinafter referred to. Fig. 11 is a view of a modification.

50 In the practical construction of my im-

proved apparatus, the general arrangement of parts is as follows: Upon a suitable platform, are mounted the main drive shaft and drive mechanism. Upon such shaft, is loosely journaled a pair of independently 55 operated winding drums, provided with independently operated clutch devices, whereby such drums can be held for rotation at varied speeds by the uniform revolution of the drive shaft, and to such drums are connected 60 the ends of a pull rope, the loop portion of which is carried into the swamp to the desired point, where it passes over a "swamp" sheave fixedly held, at the point from which it is desired to pull the logs; usually by connecting 65 it to a large tree or stump. Rope laying devices are also mounted upon the platform, one for each drum, which are independently operated by the drums at varied speeds, so as to move the opposite ends of the rope laterally at a speed proportionate to the varying 70 diameters of the drum and rope coil, and the varied revolution of such drum.

In the use of the apparatus the rope is operated to pull reversely, *i. e.*, after a log or 75 logs have been attached to the rope (in any ordinary manner) at one side, the drum on the respective side winds up, to pull the log toward it, while the opposite drum unwinds, until such log reaches the collecting lagoon, 80 when it is detached from the rope. At this time another log is attached to the opposite rope section at a point near the "swamp" sheave and the revolutions of the drums reversed, until such log is carried inward to the 85 lagoon.

Referring to the accompanying drawings A indicates a suitably arranged platform or frame work usually termed in this art "the floating boat" upon which is journaled transversely in the bearings *b b*, a shaft *B*, which extends entirely across such frame. Upon this shaft are loosely mounted two drums *C*, the construction of each of which is alike, one being shown in detail in Fig. 2 of the drawings, by reference to which it will be noticed that each drum is formed of two parts *c c* bolted together. The outer ends of each section *c* is turned out and is held to fit against an annular rim or plate *L*, which strengthens 90 95 100

both ends of the drum against the pressure of the brakes and also serves to box in the brake shoes presently referred to.

Upon the shaft B between the meeting faces 5 of the dual sections of each drum are secured collars D, which serve to hold the drums in position when at work. E indicates steel cap plates made in two parts bolted together, held to slide on the shaft B and secured to flanged 10 collars f, on the outer faces of the slotted hubs F, also arranged to slide upon the shaft, such hubs carrying clutch levers G.

By referring more particularly to Figs. 2 and 3 it will be noticed that these clutch levers are pivoted at their inner ends g to the hub F, and have play in radial sockets f' formed in such hub plates and in practice six of such levers are preferably used. The outer ends of the levers G are pivotally connected 20 by the transverse pins H, to apertured lugs j, formed integral with the segmental brake shoes J fitting within the annular rims C^x of the drums. In the peripheral faces of the brake rims J is formed a series of dovetail 25 ways j' in which are driven and fitted the gum wood friction blocks K K (see Fig. 3). A pair of main operating levers M is employed for each drum, the outer ends of which are pivotally connected to brackets N on the frame 30 timbers N'; and near such ends such levers are also pivotally connected with the sliding collars E their inner ends being extended and connected with adjusting mechanisms presently referred to.

P indicates the drive gear fixedly secured 35 to the shaft B centrally thereof, which meshes with a main drive pinion R mounted on the crank shaft Q driven by the horizontal engines S S.

In practice the cranks or crank disks have 40 to be shrunk on the engine shaft and also keyed thereto on account of the rough use they have to endure. Hence it is a difficult and expensive matter to remove the engine shaft and frequently break a crank in forcing 45 it off, when it is desired to secure the pinion R in place. To overcome this difficulty I make the pinion R out of two parts as shown most clearly in Fig. 9—by reference to which 50 it will be seen that the main or body portion of the pinion has a radially extending cut out portion R', whereby it can be slipped onto the shaft sidewise thereof and fixedly held thereon to turn therewith by the ordinary 55 wedge keys r r. Near its outer cut edge the body portion has laterally extending apertured lugs r' r' with which register apertured lugs r² r², on the detachable section or plug R³ the inner end of which is concaved at r³ to 60 snugly fit the shaft while its outer end has teeth formed thereon which complete the toothed rim of the pinion. This split piece or plug is securely held in place by means of the steel bolts r⁴ which pass through the lugs r' r², the 65 nuts r⁵ and split keys r⁶ which pass through the nuts as shown.

By referring to Fig. 1 it will be noticed that each pair of main levers is arranged to be simultaneously operated, that is the clutches on each end of each drum are adapted to be moved 70 into or out of contact with the drum rims in unison. It will also be noticed that by arranging such levers in separate pairs different clutch pressures can be applied to the different drums at the same time.

In the practical application of my improved apparatus the drums work with an endless rope a mile long (more or less) the ends of which are connected to and wound in similar directions on such drums.

By constructing the clutch devices in the manner before described it will be readily understood that while the tension on one drum is sufficient to bring in a heavy eypress log, the other can be so nicely adjusted that it will operate to let the rope run off as rapidly as it is coming in on the log side. It will also be noticed that my improved clutch devices afford simple and effective means for adjusting the speed of the unwinding drum as the empty 90 drum is being filled so as to compensate for the differential increase and decrease of the diameters of such drums. As the ingoing end of the rope begins to wind upon the empty 95 drum, the clutch devices are applied to the unwinding drum, and such drum is thereby held back by the clutch pressure to run at a slower speed than the winding drum, such speed being however gradually increased (by the clutch adjustment) until the diameters of 100 both drums are equal, after which the clutch devices on the unwinding drum are released and such drum revolved at the speed desired, by the draft on the outgoing rope.

It should be stated, that should any of the 105 friction blocks get loose they will be held from falling out by the annular flanged rims L before referred to, thereby avoiding the possibility of delay in the operation of the machine. Furthermore the flange l of such rim fitting over projecting flanges of the drum sections forms a strengthening piece to resist the outward brake pressure of the clutches.

The clutch lever operating engines before referred to may be of any approved construction, but I prefer to employ the construction shown most clearly in Fig. 8, by reference to which it will be seen that two pistons T T' are used to which are connected the oppositely movable piston rods t t', the outer ends 110 of which are pivotally connected with the inner ends of the clutch levers J as shown.

U indicates the steam chest mounted over the cylinder, V the inlet, and W the exhaust ports, and Y and Z the feed ports, one of 115 which Y, extends to each end of the cylinder and discharges in front of the pistons, while the other, Z discharges into the cylinder centrally thereof.

A⁵ indicates the slide valve to which is connected the valve rod a⁵, the outer end of which connects with the operative lever B⁵, arranged

in the manner most clearly shown in Figs. 1 and 8.

The slide valve A⁵ is a double valve and when the clutches are inoperative, that is, at rest, such valve is adjusted to the position shown in Fig. 8, but when it is desired to apply the clutches, it is moved inward until the port Y is uncovered when steam will enter in front of both cylinders and draw the levers J inward and apply the clutches. It will be readily understood by referring to the aforesaid Fig. 8 that the degree of steam pressure upon the pistons depends upon the adjustment of the valve relatively to the steam supply port. To release the clutch levers the valve is moved outward until the port Y is uncovered, which allows the steam in front of such pistons to exhaust through the port W, and the same adjustment outward will uncover the port Z and permit of the steam entering between the pistons to force them outward. To allow the piston rods to vibrate they are pivotally connected to the pistons and pass through the pipes F^X, which operate through the stuffing boxes in a well known manner.

While I prefer steam power for applying the clutch devices, I desire it understood that I do not limit myself to such means, as I may use hand power for such purpose, as for instance such as shown in Fig. 10. In this case I employ for each set of clutch levers M a rotary shaft having right and left screw threads on which are fitted internally threaded collars C⁵ pivotally connected with the inner ends of the levers M, the inner ends of such threaded shaft having hand wheels D⁵, disposed within convenient reach of the operator. By this construction the operator by turning the hand wheels can apply the clutch members to the desired tension in a quick, effective and convenient manner.

In an apparatus of this kind to render it effective for the purpose desired it is absolutely necessary that the rope be distributed and laid evenly and regular upon the drums. To this end I have provided rope laying devices connected with and operated by the drums, such devices being most clearly shown in Figs. 4, 5 and 6 of the drawings. One of such rope laying devices is employed for each drum and each of such devices consists of four upright posts E⁵ mounted upon the floating boat or body and disposed in front of the winding drums.

Upon brackets F⁵ secured to the posts E⁵ are mounted one above the other two shafts G⁵ G⁵ which are geared with the drums as shown. Each of these shafts has an endless screw or channel way g⁵ and upon it are mounted smooth bore apertured hub sections H⁵ H⁵, between which sheaves I⁵ I⁵ are held to turn upon and move laterally on the screw shafts G⁵. The hub sections H⁵ H⁵, which are arranged to be moved crosswise back and forth on the screw shafts G⁵, are held in a rigid and

correct position by means of four upright shafts J⁵ J⁵.

K⁵ indicates two revolving vertical guide rollers on each side of the machine which 70 guide the rope and lay it properly on the drum, as it comes in.

L⁵ indicates the spindle members (one for each screw shaft) secured to one of the hub sections, each having a stud portion l⁵ which 75 engages the endless channel way or thread on the shafts, as shown.

In practice, the draft ropes are one inch in diameter while the channelways or screw threads on the shafts are of a two inch pitch. 80 The object of making the screw thread of a two inch pitch is that at each complete revolution of the shaft, the screw shafts have but one half of a revolution. The screw on the said shafts G⁵ is a continuous thread or channel, and at the start it is cut a right hand thread until it reaches the opposite end, when a transverse channel extending half way round is cut, and then a left hand thread of the same pitch is cut which bisects the right 90 hand thread, and continues to the starting point.

In operation assuming the layer is at its innermost or starting position, the stub on the spindle member L⁵ is in the beginning of 95 the right hand thread and as the drum shaft is operated motion is imparted to the screw shafts, which slowly moves the laying device across the front face of the drum until it reaches the opposite end, at which time the 100 stud enters the transverse portion of the screw thread, when the sidewise movement of the layer is delayed, so as to permit the rope at this end to pile up one full turn before the layer proceeds on its reverse movement, which 105 takes place as soon as the shafts G⁵ shall have made their half revolution, at which time the stud enters the left hand thread thereby causing such layer to proceed back to its place of beginning, when the stud enters the opposite 110 transverse channel or threaded section and allows for a full turn at such end of the drum.

A^X indicates the "swamp" sheave, over which the looped portion of the rope passes. This sheave is chained to a stump or tree in 115 the swamp, by means of a bail a^X connected to the shaft b^X upon which the sheave proper B^X is journaled.

Owing to the great length of rope usually employed in this kind of log pulling machines, 120 it is essential that such winding rope be held from fouling or getting out of place on such sheave, particularly so when a log reaches the end of pull and a reverse motion is given to the rope. For this purpose a housing C⁶ is 125 supported over all of the sheave except its front face as most clearly shown in Figs. 8^a and 8^b of the drawings—such housing being formed of two sections bolted together as shown. Each section has its front edge bent 130 inward to a point flush with the peripheral front edge of the sheave as at c^X and its hori-

zontally depressed front ends flared outward as at d^x . By providing a housing for the sheave constructed as shown and described the rope will at all times and under all conditions be held true upon the sheave.

From the foregoing description taken in connection with the drawings the complete operation and the advantages of my improved apparatus will be readily understood. An apparatus constructed as described, presents the requisite strength, durability and capacity necessary to render its use a profitable one in collecting logs in Louisiana swamp lands where ordinary devices for such purposes cannot be successfully employed.

A further advantage of my improvement is, that in case of a log striking a stump on the way in the friction devices having only a sufficient tension to pull the clutches will slip and save the machine, while a rigid clutch would as a rule be broken. I also avoid the use of reversing engines as I make the reverse by loose drums; hence I save greatly in time by avoiding any stoppage as in case of reversing engines.

For very heavy work I use but four brake shoes in the clutch devices, each of which however is connected to the sliding hub by two radial levers, arranged as clearly shown in Fig. 11.

Having thus described my invention, what I claim, and desire to secure by Letters Patent, is—

1. An apparatus for the purpose described, comprising a movable platform, a drive shaft and driving mechanism mounted thereon, a pair of winding drums loosely mounted on such shaft, independently operated brake devices for clutching the drums to the shaft, a fixed swamp or anchor sheave and the pull rope passed over such sheave, and having its ends connected to drums, all arranged substantially as and for the purposes described.

2. In an apparatus for the purpose described, in combination, the floating boat or platform, the drive shaft and drive mechanism mounted thereon, a pair of winding drums loosely mounted on such shaft, independently operated brake devices for clutching such drums to the shaft, the fixed swamp or anchor sheave, the pull rope passed over such sheave, its ends connected to the drums, and rope laying devices mounted on the platform in advance of the drum, all constructed and arranged substantially in the manner and for the purposes described.

3. In a log pulling device, the combination, with the main or drift shaft, of winding drums loosely mounted thereon, each formed of two sections bolted together, and each section having extending flanges at their outer ends and clutch devices mounted on the shaft arranged

to be moved into contact with the internal face of such extended flanges, substantially as described.

4. In a log pulling apparatus, substantially as described, the combination with the main drive shaft, a drum loosely mounted thereon having projecting flanges at its ends of sliding hubs mounted on said shaft, radial clutch levers pivoted at their lower ends in such hubs, their outer ends having segmental brake shoes pivotally connected thereto, main operating clutch levers pivotally connected to the drum frame and to the sliding collars, and means for simultaneously operating such main clutch levers, all for the purpose shown and described.

5. The combination with the drum shaft, a drum loosely mounted thereon, the sliding clutch hubs, the clutch levers pivoted at their inner ends to such hubs, their outer ends carrying segmental brake shoes, adapted to engage the drums, of a pair of operating levers, one for each sliding clutch, said levers pivoted at one end to the drum frame, and connected with the sliding clutches near such end, and device connected to the free ends of the said levers adapted to simultaneously move such levers toward or from each other to adjust the clutches, substantially as and for the purpose described.

6. In a log pulling machine, the combination with the drum shaft and means for rotating it, of a winding drum loosely mounted thereon having flanged outer edges sliding clutch hubs mounted on such shafts, provided with pivotal clutch arms carrying clutch sections at their outer ends having detachable brake blocks and annular rims projecting over such blocks, and each formed with flanges extended over the flanges outer edges of the drums and means for operating the clutch levers, all substantially as and for the purpose described.

7. In a log pulling apparatus substantially as described, the combination with the drum shaft, the flanged winding drums loosely mounted thereon the slideable clutch hubs held to turn with such shaft, having radially expandible brake members adapted to engage the flanges, of brake levers pivoted to the drum frame at one side and to the slideable clutch hubs near such end, oppositely movable plunger rods connected to the free ends of such levers, a steam cylinder, pistons connected to such rods operating in such cylinder and a steam chamber, a slide valve inlets and outlets in said chamber, and a valve lever, all arranged substantially as shown and for the purpose described.
